ADJUSTABLE STANDARD FOR VEHICLE JACKS AND THE LIKE

Fredrick W. Coffing, Danville, Ill., assignor to
Coffing Hoist Company, Danville, Ill., a corporation

Application April 12, 1946, Serial No. 661,736

7 Claims. (Cl. 248—355)

1

This invention relates to a linearly extensible standard suitable for vehicle jacks, shores, etc. but not necessarily restricted to these specific uses.

The chief object of this invention is to provide a standard which may be readily adjusted to extended condition, which is automatically locked in extended relation and which is readily released and collapsed to contracted position all without the use of a central actuator or control element.

The chief feature of the present invention resides in the self-sustaining ratchet acting head carried by one of the relatively extensible elements and the cooperating portions of the other element of said elements whereby the elements may be readily extended held, or collapsed as desired without an additional actuator.

Other objects and features of the invention will be set forth more fully hereinafter.

The full nature of the invention will be understood from the accompanying drawings and the following description and claims.

In the drawings:

Fig. 1 is a longitudinal sectional view through two telescopically associated tubes, the head structure associated therewith being shown in elevation, parts being illustrated in the locked position.

Fig. 2 is a similar view of the same parts in a released position.

Fig. 3 is a transverse sectional view taken on line 3—3 of Fig. 1 and in the direction of the arrows.

Fig. 4 is an elevational view, at right angles to that of Fig. 1 and of the head structure.

Fig. 5 is an elevational view of a vehicle jack with the invention included therein.

In Figs. 1 and 2 of the drawings 10 indicates an outer tube herein having opposite longitudinal series of transversely aligned seats in the form of cut-outs or slots 11. Within the same is a slightly smaller tube 12.

Rigidly secured in the lower end thereof is the neck 13 of the head structure. The head 14 proper provides shoulder 15 bearing against the adjacent end of tube 12. The head 14 herein conforms to the interior of tube 10. It is slotted diametrically as at 16 and transversely bored as at 17. Slots 16 extends to the end of head 14 remote from shoulder 15. Pin 18 in bore 17 passes through slot 16. It is of a length as shown so it cannot escape longitudinally as long as confined by tube 10.

A pair of scissor arranged dogs or pawls 19 have tapered jaws 20 and offset extensions 21. These

2

dogs have bearing jaws 22. The extensions lap each other and are apertured at 23, which apertures are aligned and therein is positioned shaft or pin 18. Hence the two pawls are pivotally mounted and on a common pivot and are nestable in the slot 16 except to the extent noted in Fig. 2 when collapsed and to the extent noted in Fig. 1 when extended.

Means for normally constraining the dogs or pawls to extended position comprises a single spring having the coiled central portion 24 and the arms 25 which terminate in oppositely directed angular ends 26 seatable in the apertures or seats 27 in said dogs. Note in Fig. 4 that portions of the spring are nested in slot 16 and in Fig. 3 so that the clearance provided by the offsetting of portions 21 permits the anchoring of the springs thereto without interference. The lengths of the angular ends are such that neither can escape from its seat.

Operation

Whenever it is desired to extend or collapse the structure the two tubes are slightly extended. In this action cam faces 28 of the dogs are engaged by the upper face of notches or slots 11 and the pawls are tilted in opposition to the spring means. When the pawls are completely retracted from the notches, if step by step adjustment is not desired, the two tubes are relatively rotated so that the dogs then are aligned with and bear upon parts of tube 10 which have no notches. The tubes can be freely extended or collapsed until the desired effective tube length is attained. Then the tubes again are relatively rotated either the balance of 180° or reversely until the dogs are aligned with the two longitudinal series of notches. When so aligned and the tubes are slightly extended or collapsed, the dogs register with a transversely aligned pair of notches. When load is applied to tube 10 the pawl upper jaw surfaces 30 which are curved, bear upon the root 31 of slot 16 and the jaws 22 bear upon the lower walls of notches 11. Any other adjustment desired is affected by repeating the foregoing cycle.

Herein by way of example only the adjustable standard is illustrated in Fig. 5 as incorporated in a vehicle or like jack disclosed in Patent No. 2,506,705 of May 9, 1950, entitled Cable or Chain Jack.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. An adjustable standard and the like comprising an outer elongated tubular member, an inner member telescopically associated therewith having a head rigidly mounted on said inner member, the outer member having two rack arranged series of seats upon its interior and upon opposite sides thereof, said head having a transverse slot therein, a pair of oppositely directed pawls seatable in the slot and pivotally mounted, the pawls having slot root engagement and disengagement with said rack seats for retention and release purposes, and spring means associated with both pawls for simultaneously constraining the same outwardly for engagement purposes, said pawls upon relative member extension being tilttable for disengagement purposes, the interior of the outer member and the exterior of the inner member being substantially cylindrical and having a slideable frictionless fit therebetween, partial relative rotation of said members following relative member extension releasing of the pawls effecting disalignment of the pawls relative to the rack arranged seats for single rapid length adjustment greater than adjacent spacing.

2. An adjustable standard and the like comprising an outer elongated tubular member, an inner member telescopically associated therewith having a head rigidly mounted on said inner member, the outer member having two rack arranged series of seats upon its interior and upon opposite sides thereof, said head having a transverse slot therein, a pair of oppositely directed pawls seatable in the slot and pivotally mounted, the pawls having slot root engagement and disengagement with said rack seats for retention and release purposes, and spring means associated with both pawls for simultaneously constraining the same outwardly for engagement purposes, said pawls upon relative member extension being tilttable for disengagement purposes, said spring means comprising a central coiled portion, a pair of arms extending thereupon and two anchoring ends remote from the central portion.

3. An adjustable standard and the like comprising an outer elongated tubular member, an inner member telescopically associated therewith having a head rigidly mounted on said inner member, the outer member having two rack arranged series of seats upon its interior and upon opposite sides thereof, said head having a transverse slot therein, a pair of oppositely directed pawls seatable in the slot and pivotally mounted, the pawls having slot root engagement and disengagement with said rack seats for retention and release purposes, and spring means associated with both pawls for simultaneously constraining the same outwardly for engagement purposes, said pawls upon relative member extension being tilttable for disengagement purposes, both pawls having offset portions which lap in the slot and having a common pivotal axis and a spring means comprising a central coil portion, a pair of arms extending therefrom to the pawls and terminating in angular ends associated with the pawl offset portions.

4. An adjustable standard and the like comprising an outer elongated tubular member, an

inner member telescopically associated therewith having a head rigidly mounted on said inner member, the outer member having two rack arranged series of seats upon its interior and upon opposite sides thereof, said head having a transverse slot therein, a pair of oppositely directed pawls seatable in the slot and pivotally mounted, the pawls having slot root engagement and disengagement with said rack seats for retention and release purposes, and spring means associated with both pawls for simultaneously constraining the same outwardly for engagement purposes, said pawls upon relative member extension being tilttable for disengagement purposes, the root of the slot being arched and the confronting faces of the pawls nested in the slots being correspondingly arched for bearing purposes, the opposite faces being of bearing type, and a cam type end face on the front end of each pawl.

5. An adjustable standard and the like comprising an outer elongated tubular member, an inner member telescopically associated therewith having a head rigidly mounted on said inner member, the outer member having two rack arranged series of seats upon its interior and upon opposite sides thereof, said head having a transverse slot therein, a pair of oppositely directed pawls seatable in the slot and pivotally mounted, the pawls having slot root engagement and disengagement with said rack seats for retention and release purposes, and spring means associated with both pawls for simultaneously constraining the same outwardly for engagement purposes, said pawls upon relative member extension being tilttable for disengagement purposes, the root of said slot being arched and the confronting faces of the pawls seated in the slot being correspondingly arched for bearing purposes, the opposite faces being of bearing type, and a cam type end face on the free ends of each pawl, the adjacent ends of said pawls being offset from the body portion thereof and lapped in the slot and having a common pivotal axis.

6. An adjustable standard and the like comprising an outer elongated tubular member, an inner member telescopically associated therewith having a head rigidly mounted on said inner member, the outer member having two rack arranged series of seats upon its interior and upon opposite sides thereof, said head having a transverse slot therein, a pair of oppositely directed pawls seatable in the slot and pivotally mounted, the pawls having slot root engagement and disengagement with said rack seats for retention and release purposes, and spring means associated with both pawls for simultaneously constraining the same outwardly for engagement purposes, said pawls upon relative member extension being tilttable for disengagement purposes, the root of said slot being arched and the confronting faces of the pawls seated in the slot being correspondingly arched for bearing purposes, the opposite faces being of bearing type, and a cam type end face on the free ends of each pawl, and the spring means being singular and comprising a central coiled portion, a pair of arms extending therefrom and two angular extension ends remote from the central portion.

7. An adjustable standard and the like comprising an outer elongated tubular member, an inner member telescopically associated therewith having a head rigidly mounted on said inner member, the outer member having two rack arranged series of seats upon its interior and upon opposite sides thereof, said head having a trans-
